Primary Examiner—Ruth McInroy

(57) **CLAIM**

The ornamental design for a microwave oven, as shown and described.

DESCRIPTION

FIG. 1 is a perspective view of a microwave oven in accordance with my new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a left elevational view thereof;
FIG. 7 is a right elevational view thereof; and,
FIG. 8 is a perspective view thereof, with the door to the oven chamber in an open position.

The details shown in broken lines form no part of the claimed design.

1 Claim, 8 Drawing Sheets
